UNITED STATES PATENT OFFICE.

JOHN THOMAS BOND, OF PALATKA, FLORIDA.

INSULATOR.

No. 927,321.

Specification of Letters Patent.

Patented July 6, 1909.

Application filed March 13, 1908. Serial No. 420,797.

To all whom it may concern:

Be it known that I, JOHN T. BOND, a citizen of the United States, and a resident of Palatka, in the county of Putnam and State 5 of Florida, have invented certain new and useful Improvements in Insulators, of which the following is a specification.

My invention is an improvement in insulators, and consists in certain novel constructions and combinations of parts hereinafter described and claimed.

Referring to the drawing forming a part hereof, Figure 1 is a perspective view of the improvement in place on the cross arm. Fig. 2 is a vertical section through the insulator clamp and cross arm. Fig. 3 is a section on the line 3—3 of Fig. 2. Fig. 4 is a perspective view of a modified form of insulator. Fig. 5 is a central longitudinal section. Fig. 6 is a side view showing a modified form of clamp, and Fig. 7 is a similar view showing the manner of securing two insulators by a double clamp.

In the present embodiment of the invention, the insulator comprises a body portion 1, and an integral base 2, of non-conducting material the body portion being cylindrical, and the base of substantial rectangular form.

The free end of the insulator is rounded in the usual manner as at 3, and at substantially the longitudinal center of the insulator an annular groove 4 is provided, the walls of the groove being under-cut as at 5 and 6, and the under-cut edges being provided with inwardly projecting marginal flanges 7, as shown in Fig. 2.

A plurality of longitudinal spaced grooves are provided in the wall of the body portion, 40 the said grooves intersecting the annular groove 4, and stopping thereat as in Figs. 4 and 5, or extending therebelow as in Figs. 1 and 2.

A petticoat 8 is provided below the groove, 45 and the insulator may be also provided with the central longitudinal screw threaded opening 9 for engagement by the screw threaded pin on the cross arm 11, the opening extending entirely through the insulator as shown.

In Figs. 1 and 2, is shown a preferred form 50 of clamp for securing the insulator to the cross arm. The clamp comprises a body portion 12 having a central opening for permitting the passage of the body portion of the insulator, and the side portions 13, 14 bent at right angles to the body portion and

embracing the sides of the cross arms. A part of the side portions is cut away as at 15, and the said side portions are of a length to extend below the cross arm as shown in Figs. 60 1 and 2, and are provided with openings 16 for receiving a bolt 17, connecting the opposite side portions and secured in place by a nut 18.

In Fig. 6, the clamp comprises U-shaped 65 members whose body portion 19 rests upon the base, and whose arms extend transversely of the cross arm. The corresponding arms of the two clamps cross at the lower edge of the cross arm, and a bolt 21 passing 70 through the inter-section of the arms secures the clamp in place. In Fig. 7, the clamp comprises a pair of bands which encircle the cross arm and extend over the base of the insulators, which are arranged above and below 75 the cross arm. The members of the clamp are crossed, and a bolt 23 extends through the said members and the cross arm to secure them in place.

In the construction shown in Figs. 4 and 5, 80 the body portion 24 of the insulator is provided with an annular groove 25 having its upper wall under-cut as at 26, while the lower wall is rounded downwardly as at 27, to deflect moisture which might otherwise 85 collect in the groove. The longitudinal grooves 28, extend only to the bottom wall of the annular groove. The insulator is secured in place by a screw 29 traversing an opening therein and engaging a suitable 90 support 30.

The form of insulator shown in Figs. 4 and 5 is especially designed for inside work, and for outside work where the wires pass along buildings and the like, while the form shown 95 in Figs. 1, 2, 3, 6, and 7, is adapted for pole work. The under-cut edges of the annular groove form a species of hook for retaining the wires in place and the marginal flanges 7 shown in Figs. 2, 3, and 7 assist in retaining 100 the wire in place. The peculiar form of groove is also of great assistance in stringing wires when constructing new lines or renewing old, since the wire may be laid in its grooves during the construction and afterward secured in place.

The longitudinal grooves, afford an efficient drainage for the annular groove, preventing any collection of water in the said groove, while the petticoat prevents a continuous film of moisture from forming on the insulator. It will be noticed that the longi- 110

tudinal grooves are of an equal depth with the annular groove.

It will be noticed from an inspection of Fig. 1 that the corners of the base of the insulator are provided with openings 31, in order that the insulator may be secured to a support by nails or screws.

I claim:

1. An insulator comprising a cylindrical body portion and an integral substantially rectangular base, the insulator having at approximately its center, an annular groove whose side walls are under-cut, the edges of the groove being provided with inwardly projecting marginal flanges, said insulator having a plurality of longitudinal spaced grooves, intersecting the annular groove, and extending above and below the same, the grooves being of equal depth with the annular groove, and a clamp for securing the insulator to a cross arm, said clamp comprising a body portion provided with an opening to permit the passage of the body portion of

the insulator, the base engaging against the under-side of the clamp, and side members 2 for engaging the sides of the cross piece and extending therebelow and bolts connecting the side members for securing the clamp in place.

2. An insulator comprising a cylindrical body portion and an integral substantially rectangular base, the insulator having at approximately its center an annular groove whose side walls are under-cut, the edges of the groove being provided with inwardly projecting marginal flanges, said insulator having a plurality of longitudinal spaced grooves intersecting the annular groove, and extending above and below the same, the grooves being of equal depth with the annular groove, and means for securing the insulator in place.

JOHN THOMAS BOND.
